INVENTOR
Henry F. Zahner.
Wm. G. Brown,
ATTORNEY

UNITED STATES PATENT OFFICE.

HENRY F. ZAHNER, OF KANSAS CITY, MISSOURI.

DOOR.

Application filed June 30, 1924. Serial No. 723,208.

To all whom it may concern:

Be it known that I, HENRY F. ZAHNER, a citizen of the United States, residing at Kansas City, in the county of Jackson and 5 State of Missouri, have invented certain new and useful Improvements in Doors; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 This invention relates to metallic doors and the primary object of the invention is to construct a door with a finish panel on the front, the novelty residing in the manner in which the panel is secured to the door so 20 that the connecting joint or fastening means will not be visible. The invention includes a door and a facing panel and the novel manner by which they are fastened together will be apparent by reference to the following description in connection with the accompanying drawings, in which

25 Fig. 1 is a perspective view of a compartmental device to which my invention is applied.

30 Fig. 2 is a sectional view through the door with the facing panel attached thereto.

35 Fig. 3 is a fragmentary perspective view of the door and the facing panel.

Fig. 4 is an end view of the door and

35 Fig. 5 is a fragmentary sectional view through a slightly modified form of door and facing panel.

40 The compartmental device 1 may be used for any purpose such as an oven, warming table, bin or the like and pivotally secured to the side walls thereof is a door having arms 2 and 3 of sheet metal with offset portions 4 and 5 to which are bolted the offset inturned ends or flanges 6 and 7 of the door panel 8. The ends of the door panel are 45 bent back upon themselves as at 9 and 10 and then outwardly to form the flanges 6 and 7 which are secured to the offset portions 4 and 5 by the bolts 11.

A fanciful finish panel 12 is provided, 50 the main body of the panel being offset with respect to the end portions 13 and 14 which are bent around the bent back ends 9 and 10 of the door panel 8. The ends 13 and 14 are hook shaped in cross section as indicated 55 at 15 and 16 so that they tightly embrace the ends 13 and 14 whereby the finish panel 12 is held in place.

It will be apparent of course that the fastening means will not be visible from the 60 front of the door so a very neat appearing door is provided.

In Fig. 5 I have shown substantially the same construction except that the door panel or front 8' is integral with the arms, one of 65 the arms 2' being shown. The panel 12 however is secured in identically the same way as it is in the illustrated embodiment shown in Figs. 1, 2, 3 and 4. In any event the door panel will be secured to its hinge arm intermediate the ends of the panel so that the 70 panel will have projecting edges over which the edges of the finish panel can be bent to form the securing means between the finish panel and the door panel.

What I claim and desire to secure by Letters-Patent is:

1. A door comprising a door panel, hinge arms inset from the edges of the panel so that the panel has projecting edges and a finish 80 panel having its edge bent back around projecting edges of the door panel.

2. A door comprising a panel, hinge arms projecting rearwardly from the panel, the arms being spaced from the ends of 85 the panel and a finish panel having its edges bent over and around the edges of the door panel.

3. A door comprising a panel having integral rearwardly extending hinge arms inset from the edges of the panel and a finish 90 panel bearing against the outer face of the door panel and having its edges bent around the ends of the door panel whereby the finish panel is fastened to the door panel.

55 05 In testimony whereof I affix my signature.

HENRY F. ZAHNER.
